UNITED STATES PATENT OFFICE.

WILHELM SCHAEFER, OF BERLIN-WILMERSDORF, GERMANY.

DOCUMENT FILE.

Application filed June 27, 1923, Serial No. 288,593, and in Germany June 2, 1927.

This invention relates to document files of the kind in which the inserted documents are firmly clamped by pressing arms extending transversely to the marginal border of the 5 documents and to the fold of the file.

According to the invention, a pair of clips having pressing arms extend along the fold of the folder of the file, and each clip is at its outer end pivoted transversely to a base, so 10 that it can be swung upwards away from said base.

The two clips when in their depressed clamping position are interlocked, the pressing arms thereby securely clamping the documents. 15

It has already been proposed in newspaper holders to employ a pair of aligned rods for holding newspapers firmly, each of which being pivoted and locked in the depressed position. 20 However, in such newspaper holders the said rods are located along the fold of the newspaper and hold the latter by spikes provided on the rods. Such an arrangement can not therefore be used for document files 25 with widely varying thicknesses of contents.

An embodiment of the file is illustrated, by way of example, on the accompanying drawing, in which:—

Fig. 1 is a plan of the file with the parts in 30 the clamping position,

Fig. 2 is a section along the line II—II of Fig. 1, and

Fig. 3 is a longitudinal section along the line III—III of Fig. 1, the open position of 35 the parts being indicated in dot-dash lines.

A metal base plate *a* with an upstanding clamping edge *b* is riveted along one side of the middle fold of and in a cover or folder. At each of the two transverse narrow borders 40 or ends of the base plate is a hinge strap *c*. A pair of clamping clips *d* and *d'* engage by means of bent ends in the hinge straps *c*, so that they are journaled therein. The clamping clips *d*, *d'* are formed with loops *e* and *e'*, which extend over the clamping edge *b* of the base plate and on clamping serve as pressing fingers. The free ends *f* and *f'* of the 45 clips are situated opposite one another when the clips are located in the clamping position, shown in Fig. 1. A sleeve *g* is slidably mounted on the end of the clip *f*, and a bend *h* (Fig. 3) of the clip end *f* limits the sliding displacement and prevents complete removal of the sleeve. When the ends of the clips *f* 50 and *f'* in the depressed clamping position

are approximately in alignment, the sleeve *g* is slidably moved with its free end over the free end *f'* of the clip *d'*, whereby it holds both clips down in the clamping position, as it thereby connects both parts rigidly together. In order to facilitate the slipping over, the extremity of the end *f'* of the clip *d'* is slightly bent, as shown at *i* in Fig. 3. Moreover, conveniently, the sleeve *g* is at its free end slightly cutaway underneath, so that 60 on folding down the clips, such end of the sleeve can already overlie the end *f'* of the other clip before being slidably displaced.

The rigid interconnection of the two pivoted clips in the depressed position can alternatively be effected by other means, and even in some circumstances without employing a displaceable intermediate member, by direct interengagement of the two ends of the clips when of appropriate construction. The 70 clamping clips themselves can be constructed in various forms, in particular as regards the pressing fingers.

I claim:

1. In a document file, a folder, clip means 80 divided at an intermediate portion of its length extending along the fold of said folder and pivoted at each end transversely to said fold, and a sleeve for interlocking the two portions of said clip means.

2. In a document file, a folder, a pair of 85 clips each comprising an elongated portion extending along the fold of the folder and pivoted by means of a transverse journal portion at an end of the folder, and a pressing finger extending transversely from said elongated portion, and means for interlocking the adjacent ends of said clips.

3. In a document file, a folder, a pair of 90 clips, each comprising an elongated portion extending along the fold of the folder, hinge straps on said folder and arranged transverse to said fold, transverse journals formed at the ends of said clips and journaled in said hinge straps, and a pressing finger extending 95 transversely from said elongated portion, and means for interlocking the adjacent ends of said clips.

4. In a document file, a folder, a base plate 100 having an upstanding edge and secured to said folder along one side thereof, hinge bearings on said base plate and arranged transverse to said fold at each end of said base plate, a pair of clips, each comprising an elongated portion extending along the fold of 105

110

the folder, a transverse journal received in one of said hinge bearings, and a pressing finger extending transversely from said elongated portion, and means for interlocking the adjacent ends of said clips.

5. In a document file, a folder, a base plate having an upstanding edge and secured to said folder along one side thereof, hinge bearings on said base plate and arranged transverse to said fold at each end of said base plate, a pair of clips, each comprising

an elongated portion extending along the fold of the folder, a transverse journal received in one of said hinge bearings, and a pressing finger extending transversely from said elongated portion, and a sleeve sliding on one portion of said clips and displaceable over the other portion thereof. ¹⁵

In testimony whereof I have signed my name to this specification,

WILHELM SCHAEFER.
